UNITED STATES PATENT OFFICE.

EDWARD T. McHUGH, OF HOLYOKE, MASSACHUSETTS.

MOLDER'S FLASK.

No. 928,000.

Specification of Letters Patent.

Patented July 13, 1909

Application filed November 28, 1908. Serial No. 464,914.

To all whom it may concern:

Be it known that I, EDWARD T. McHUGH, a citizen of the United States of America, and resident of Holyoke, in the county of 5 Hampden and State of Massachusetts, have invented certain new and useful Improvements in Molders' Flasks, of which the following is a full, clear, and exact description.

This invention relates to improvements in 10 corner fastenings or locks for molders' snap-flasks, in which the two right-angular separable parts of both the cope and nowel divisions of the flask are held together at diagonally opposite corners by locking snap-catches; and the object of this invention is 15 to provide interengaging corner constructions comprising distending springs and snap-catches which latter may be easily brought to locked relations for holding the 20 separable or expanding parts of the flask while in their contracted relations securely against premature release or accidental unlocking, and whereby, as required, the catches may be quickly and conveniently released so 25 that the right angular half frame portions of each flask may be automatically distended or opened.

The invention consists in the combination 30 or arrangements of parts and the constructions of certain of the parts all substantially as hereinafter described in conjunction with the accompanying drawings and set forth in the claims.

In the drawings:—Figure 1 is a plan view 35 of a snap flask, the two separable parts thereof being shown as unlocked, and in their expanded and distended relations; Fig. 2 is a plan or face view of the flask, the two side frames of which are shown as locked; 40 the position in which the flask as a whole is shown being a usual one in operating the same. Fig. 3 is an elevation showing the adjacent corner portions of the two separable parts of both the cope and nowel divisions 45 of a flask, as unlocked and separated, one of the locking devices being shown in section, as taken on the line 3—3, Fig. 1. Fig. 4 is a similar view to Fig. 3 in every respect 50 except that the two parts of both divisions of the flask are shown in their closed relations and locked. Fig. 5 is an end elevation of the locking devices at one corner of both divisions of a flask, the view being taken in the direction indicated by the arrow α in 55 Fig. 2, the snap-catches being shown in their unlocked position, with some parts in verti-

cal section as taken on line 5—5, Fig. 3. Fig. 6 is a similar view to Fig. 5, but showing the snap catches in their locked positions. Fig. 7 is a perspective view of several of 60 the coacting parts of the snap-catch in separated relations.

In the drawings, A represents the cope and A' the nowel or drag of a flask, and as is common in snap-flasks, each division consists, 65 instead of one complete four-sided frame, of two half-frames a and b each of which comprises a side wall and an end wall, and which, when united in their proper relations to each other by the corner locks or snap-catches B, usually surround a light (four 70 sided) frame C which is separately supported within the said frames a and b , by the short dowel pins c . The frames C are 75 strengthened and supported by the inclosing snap-flask frames a and b during the operation of ramming the sand about the properly introduced patterns, the rapping of the latter and the other well known operations common to molders' trade, all requiring a 80 strong and rigid flask; but on the completion of the mold within the inside frames C, the heavy flask-frames a and b are not 85 necessary for the successive operations of making the casting (especially light castings) and are, therefore, removed, and are repeatedly used with other inside frames C.

The snap-catch or lock,—duplicated for the corners of the sectional flask,—which constitutes the present invention will now 90 be described in detail. The adjacent separable corner portions of the flask-frames a and b of both the cope and nowel divisions of the flask, are provided with the lock supporting plates 10 and 12 respectively which 95 are securely fitted and attached thereto, as shown in dotted line in Figs. 1 and 2, and which have angularly projecting end flanges 14 and 15 respectively which extend outwardly from the plate-portions 10 and 12 100 at an angle of about 45 degrees. The flanges 14 and 15 of lock-plates 10 and 12 have, formed centrally thereon, cylindrical bosses 16 and 17 respectively which are axially in line with each other. The bosses 17 on the 105 flanges 15 of lock plates 12 rigidly support in threaded engagement therewith one end of the guide bolts or bars 18, which extend therefrom to and loosely through a central bore in the bosses 14 of lock plates 10, and 110 serve to steady and guide the approached ends of the flask frames a and b and to main-

tain them in relations to each other which constitute in practice a four-sided flask-frame, the diagonally opposite corners of which are slightly separable.

- 5 The degree of separation which the lock provided corners of the frame parts *a* and *b* have relative to each other is regulated by the stop bolts 19 which are two in number for each corner device, and are located on 10 either side of the guide bolts 18. One end of each stop bolt 19 is secured by a screw-threaded engagement with the flange 14 of lock-plate 10 and each bolt projects therefrom to and loosely through the flange 15 of 15 the adjacent lock-plate 12, and both bolts are provided on their end portions which extend through the flanges 15, with nuts 20 which, as clearly shown in Figs. 3 and 4, prevent the withdrawal of the stop-bolts 19, 20 through the flange portions 15.

The separable parts of the flask frame *a* and *b* are normally held apart from each other by the spiral spring 21 which is carried on the bolt 18 and the end portions of 25 which are supported within sockets in the adjacent faces of the flanges 14 and 15.

The means provided for holding the frame parts *a* and *b* in close and constricting engagement about the inside mold-containing 30 frame C consists in a latch, about to be described, which engages the guide-bolt 18.

The cylindrical axially bored boss 16, as will be best seen by a reference to Figs. 3 and 5 of the drawing has formed on one side 35 thereof a transversely extending slot 22, within which slides the vertical bolt-engaging detent or catch member 25 of the latch D carried as a right angled extension of an approximately semi-circular plate 26.

40 The guide bolt 18, see Figs. 3 and 4, has a notch 27 formed at a point thereon so located that to bring it into a position in which the latch 25 may engage it the two parts *a* and *b* of the flask are approached substantially to their fullest extent against the compression of the spiral spring 21.

To automatically bring the latch 25 into locking engagement with notch 27 of the guide-bolt 18 and to securely hold it against 45 accidental disengagement therewith, during the somewhat violent handling to which the flask may be subjected while in its locked position, a spiral spring 30 is provided on the opposite side of this boss 16 from the latch detent 25 and in line therewith. The end of the spring 30 which rests on boss 16 is engaged by the teat or projection 31. The recoil of the spring 30 against the latch 25 whereby the said latch is caused to be closely 55 pressed against the bolt 18 is through the stirrup shaped frame E which comprises a cylindrical spring socket 36 from which two oppositely located and parallel legs 37 extend on either side of the boss 16 to and 60 through the semi-circular member or latch 65

plate 26 of the latch D, their screw threaded ends being provided with the nuts 39 which secure the latch plate as one to the stirrup. The legs 37 of the stirrup E are guided relatively to the boss 16 in vertical side grooves 70 in the boss 16, see Fig. 7.

The location of the above described latches D and stirrups E relatively to the bosses 16 of the frame locks of the cope part of the flask are opposite to those of the nowel part, 75 thereby bringing the latches D of the two divisions of the flask within easy reach of each other, so that when the flask is, for instance, brought to the carrier supported position shown in Fig. 2, a forcing of all the 80 latch members 26 toward each other, manually, serves to automatically release the corner catches of the divisions of the flask and permits them to be automatically expanded and entirely free for removal from the mold 85 frames C to be then used for the making of further molds.

I claim:—

1. A flask section comprising separable L-shaped half frames provided at their contiguous ends, at the diagonally opposite corners of the flask section with separated obliquely outwardly extending projections, one of each pair being provided with an aperture and the other with an affixed bolt 90 extending through the aperture and having a catch shoulder, the bolt carrying projection having guide holes at both sides of the bolt and the other projection having affixed parallel bars playing through said 100 holes, and provided with stop nuts at their free ends, a spring in compression between the pair of projections, and a spring latch supported by, and movably guided relatively to, the apertured projection and 105 adapted to normally engage in the catch shoulder of the bolt when the flask portions are moved to contracted relations.

2. A flask section comprising right angularly disposed separable side walls provided at their contiguous ends with separated obliquely outwardly extending projections one thereof being provided with an angular outwardly extending boss, and apertured through said boss provided portion, said 110 boss having a slot extending from its exterior to communication with said aperture and having opposite side guiding recesses, the other projection being provided with a bolt extending through said apertured boss 115 and having a catch shoulder, a spring having a separating reaction between said projections, a stirrup shaped frame straddling about the said boss and guided in the opposite side recesses thereof and carrying, by 120 and between the extremities of its legs a plate having an angularly extended latch member disposed in the slot of the boss, and a spring in compression between the boss 125 and the head of the stirrup frame for force- 130

ing the latter to move the latch carried thereby into engagement with the catch shoulder of the bolt.

3. A flask section comprising right angularly disposed separable side walls provided at their contiguous ends with separated obliquely outwardly extending projections, one thereof being provided with an angular outwardly extending boss and apertured through said boss provided portion, and the other projection being provided with a bolt extending through said aperture and having a catch shoulder, a spring having a separating reaction between said projections, a 15 stirrup shaped frame having a straddling and guided relation to said boss and carrying by and between the extremities of its legs a latch, and a spring operative between the boss and stirrup frame for forcing it to bring the latch into engagement with the 20 catch shoulder of the bolt.

4. A flask section comprising right angularly disposed separable side walls provided at their contiguous ends with separated obliquely outwardly extending projections, 25 one thereof being provided with an angular outwardly extending boss, and having an aperture through said boss provided portion, and the other projection being provided with a bolt playing through said aperture and having a catch shoulder, a spring having a separating reaction between said 30 projections, and a latch movably mounted on the said boss and spring pressed for an engagement in the catch shoulder of the 35 bolt.

Signed by me at Springfield, Mass., in presence of two subscribing witnesses.
